Primary Examiner — Justin M Jonaitis*Assistant Examiner* — Samantha K Pollack(74) *Attorney, Agent, or Firm* — JEEN IP LAW, LLC(57) **CLAIM**

The ornamental design for a LED light therapy vest, as shown and described.

DESCRIPTION

FIG. 1 is a front, right and top perspective view of a LED light therapy vest, showing my new design;

FIG. 2 is a perspective view thereof, shown in a disassembled condition;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines shown in the drawings illustrate portions of the LED light therapy vest that form no part of the claimed design.

1 Claim, 8 Drawing Sheets(56)
